United States Patent Office.

CHARLES HENRY KIMBALL, OF CHELSEA, MASSACHUSETTS.

Letters Patent No. 87,781, dated March 16, 1869.

IMPROVEMENT IN TICKET-HOLDERS

The Schedule referred to in these Letters Patent and making part of the same.

To all persons to whom these presents may come:

Be it known that I, CHARLES HENRY KIMBALL, of Chelsea, in the county of Suffolk, and State of Massachusetts, have invented a new and useful Ticket-Holder; and do hereby declare the same to be fully described in the following specification, and represented in the accompanying drawings, of which—

Figure 1 is a top view, and

Figure 2, a side elevation of it in a folded state.

Figure 3 is a side view of it, as applied to the rim of a hat.

Figure 4 is a top view of it, as it appears with the clamp raised at a right angle with the nippers.

The purpose of the said ticket-holder is to support a railway-passenger's ticket, and fix it to the rim of the hat of a person, in order that such ticket may be observed to advantage, from time to time, by a conductor of a railway-carriage in which the person having the ticket fixed to his hat may be seated.

The article is composed mainly of a spring-clamp, A, and a pair of nipper-levers, B C, provided with a closing-spring, D.

The spring-clamp is composed of a jawed bar, a, and a jawed spring, b, fastened together at or near the lower end of the latter, they being formed and arranged in manner as represented.

There is fastened to the lower part of such clamp a projection, E, which is hinged to one end of the upper

of the nipper-levers B C, and rests on the lower of such levers.

The said two levers are hinged together at or near their middles, and provided with a spring, D, which is arranged between their tails, and fastened to one, and, at or near its fore end, bears against the other of them, the whole being as shown in the drawings.

In using the article, the parts should first be brought into the positions shown in fig. 3; that is, the clamp A should be turned up at a right angle, or thereabout, with the nippers, after which the railway-passenger ticket should be inserted between the jaws of the clamp. The ticket-holder should next have the rim of the hat of the passenger placed between the jaws of the nipper-levers, the spring afterward closing them upon the rim, so as to firmly hold them in connection therewith. The hinge-piece or projection E, by being borne against the rim, will hold the clamp in its angular position with respect to the nippers.

By folding the clamp down upon the nippers, the whole article will be in a favorable condition for being carried in the vest-pocket of its owner.

I claim the new article of manufacture, or ticket-holder, made substantially as described and represented.

CHAS. HENRY KIMBALL.
